GAS AND OIL SEPARATOR

Milon J. Trumble, Alhambra, and William L. Seeley, Los Angeles, Calif., assignors to Processco, Limited, San Francisco, Calif., a corporation of Nevada

Application December 3, 1930. Serial No. 499,738

8 Claims. (Cl. 137—68)

This invention relates to apparatus for separating gas from oil under pressure containing the same, and the objects of the invention are to provide apparatus for carrying out the separation in an automatic manner actuated by the pressure of the contained gases, and particularly to the construction of the float controlled oil valve forming the most important feature of the apparatus. Other objects of the invention will appear in the following description and in the accompanying drawing.

In the drawing Fig. 1 is a vertical section taken through the tank of our apparatus while showing the valve housing in full.

Fig. 2 is a cross section of the apparatus as seen from the line 2—2 of Fig. 1.

Fig. 3 is an enlarged elevation of the valve discharge end as seen from the line 3—3 of Fig. 2.

Fig. 4 is a vertical section of a discharge valve similar to that shown in Fig. 2 but of modified form.

In further detail, the invention comprises a suitable closed chamber adapted to withstand a moderate pressure such as a cylindrical tank 1 fitted on top with a gas discharge pipe 2 provided with an automatic pressure regulator 3 and pressure gage 4, while at one side of the tank is an oil delivery pipe 5 provided with a downwardly turned inner end 6 directing a stream of mixed oil and gas onto the body of oil 7 in the tank for liberation of its gas to the space above the oil while the rising and falling level of the oil is used to control the discharge of oil from the tank through the special float valve arrangement.

This float valve arrangement includes a cylindrical housing 8 bolted at 9 to a relatively large flanged collar 10 welded firmly to the tank by the addition of a reinforcing plate 11 as indicated.

Bolted at one end of the housing 8 is a discharge nozzle or pipe connection 12, while bolted to the opposite end of the housing is a bonnet 13 fitted with a stuffing box 14, through which passes a stem 15 of a rotary hollow cylindrical valve or member 16. This valve member 16 is somewhat smaller in diameter than the interior of the housing 8 so as to provide a gas pressure space around the valve member 16, and this space extends partially over the discharge end of the valve though more above the stem end of the valve as indicated at 17 so that the gases under pressure entering the space freely from the tank through collar 10 will react equally about

the outer sides of valve member 16 while resiliently urging its flat discharge end 16' against a fixed flat seat 18 pressed snugly in place in nozzle 12 as indicated.

The discharge end of the valve member 16 is formed with a circular boss or shoulder 16'' concentric with valve stem 15 rotatably seated in the circular depression in which the seat is supported, while both the end wall 16' of the valve and the seat 18 are pierced respectively with segment-shaped ports 19, 20 eccentrically located with respect to the axis A of the valve adapted to be brought into coinciding relation or closed off upon partial revolution of the valve.

The stem of the valve is preferably fitted with an annular ball bearing 21 to centralize it, and at the outer end of the stem is a crank 22 pivotally connected to the upper end of a rod 23, in turn pivoted at its lower end to a crank 24 secured to the end of a short shaft 25 rotatably mounted in an outwardly extending pocket 26 formed on or welded to the side of the tank. The end of the shaft carrying the crank projects through a stuffing box 27 so as to be gas-tight while the other end works in a blind bearing as indicated in Fig. 2, and secured to the central portion of the shaft within pocket 26 is a horizontally extending arm 28 carrying at its end a float tank 29. This float tank is of hollow metal construction and provided with a small tube 30 which extends tightly through the top of the tank to terminate with its lower open end adjacent the bottom of the tank, and the upper open end of which tube is elevated above the tank and turned downwardly as indicated.

Oil is conveyed into the interior of the valve by a pipe 31 which extends through the collar 10 and is threaded or welded through a side opening in the rotatable valve member 16. This pipe has a downwardly extending section 31' which always dips below the surface 7 of the oil, and swings in the oil as the valve turns.

Connecting rod 23 is adjustable in various holes indicated along cranks 22 and 24 to vary the throw or setting of the valve, though the size of the collar 10 in relation to pipe 31 is usually so proportioned as to form a definite stop at both full open and full closed position of the ports 19, 20.

In operation of the apparatus, the gas liberated from the oil builds up a pressure as regulated by automatic valve 3 and keeps the oil forced up pipe 31 through the interior of the rotatable valve member and out through ports 19, 20, pipe 31' swinging in the oil in conformity to the turn-

ing of the valve by rising or falling of the float valve.

By this construction the only valve surface to be kept tight is the end against the flat seat, and since the oil is delivered directly to the interior of the valve there is no possibility of the least particle of sand or grit carried by the oil working into the parts to cause injury, and the gas which is under the same pressure as the oil functions as a valve balancing agent around the sides of the valve yet on account of the areas exposed with a resilient seating action on the valve surfaces.

Fig. 4 shows modifications in the construction of the overflow valve. The view is a vertical section and indicates the housing of the valve at 32 secured to the wall of the tank 33, hollow valve member 34 mounted in the housing and provided with a stem 35 projecting through a stuffing box 36 and fitted with a crank 37 at its end corresponding in all respects with the crank 22 of Fig. 1 for similar operation of the valve by a float and linkage substantially as indicated in Figs. 1 and 2.

Valve member 34 is ported at 34' through one side for discharge, and the outer wall of this member may be suitably spaced away from the housing wall over an area to provide a partial balancing of the member by external gas pressure from the tank through the open inner end of the housing all as indicated, while a short inlet pipe 38 for oil extends centrally from the end of the valve member carrying at its end a packed swing joint or swivel connection 39 from which a vertical pipe 40 hangs with its lower end in the oil. By this arrangement pipe 40 will remain stationary, or may be so held by a fork 41 secured inside the tank, while pipe 38 turns with the valve member.

It is manifest that without further drawings that this swivel joint may be placed on the valve member instead of on the pipe 8 extending therefrom if desired.

We claim:

1. A valve comprising a housing, a hollow valve member rotatably mounted in said housing ported for inlet and outlet of a fluid, and a pipe connected to the inlet port of said member arranged for delivering a fluid to the interior of said member for discharge through its outlet port, said housing providing a space at the sides of said rotatable member, and means for introducing a balancing fluid under pressure to said space.

2. A valve comprising a housing, a hollow valve member rotatably mounted in said housing ported for inlet and outlet of a fluid, and a pipe secured to the inlet port of said member arranged for delivering a fluid to the interior of said member for discharge through its outlet port, said housing providing a space at the sides of said rotatable member adapted for the reception of a gas under pressure.

3. A valve comprising a housing, a hollow cylindrical valve member rotatably mounted in said housing, a seat in said housing against which one end of said member contacts, ports in said seat and said end of said member eccentrically arranged with respect to the axis of rotation so as to be closed and opened upon rotation of the member,

a pipe entering said member for delivering a fluid thereto for ejection from said ports, said housing adapted for securing to a tank, said pipe provided with an extension arranged to dip into a liquid contained in said tank, and a float on said liquid provided with connections for turning said valve member.

4. Apparatus of the character described comprising a tank adapted to contain a liquid and a gas under pressure above the liquid, a discharge valve on said tank for the liquid, means controlling the discharge of liquid through said valve actuated by the level of the liquid in said tank, and means for balancing said valve by gas from the gas space within said tank.

5. Apparatus of the character described comprising a tank adapted to contain a liquid and a gas under pressure above the liquid, a discharge valve on said tank for the liquid, means controlling the discharge of liquid through said valve actuated by the level of the liquid in said tank, said valve located at a point above the liquid, and a pipe from said valve extending downward into the liquid whereby the liquid is forced up to the valve by said gas under pressure, and means for balancing said valve by gas from the gas space within said tank.

6. Apparatus of the character described comprising a tank adapted to contain a liquid and a gas under pressure above the liquid, a valve housing provided with an inner rotatable hollow valve mounted on the side of said tank above the liquid level, a tubular connection between the tank and valve exposing a portion of said hollow valve to the tank interior, a pipe projecting from said hollow valve through said tubular connection to the tank and provided with an extension directed downwardly into the liquid.

7. Apparatus of the character described comprising a tank adapted to contain a liquid and a gas under pressure above the liquid, a valve housing provided with an inner rotatable hollow valve mounted on the side of said tank above the liquid level, a tubular connection between the tank and valve exposing a portion of said hollow valve to the tank interior, a pipe projecting from said hollow valve through said tubular connection to the tank and provided with an extension directed downwardly into the liquid said tubular connection being relatively large to permit oscillation of said pipe upon rotary movement of said valve.

8. Apparatus of the character described comprising a tank adapted to contain a liquid and a gas under pressure above the liquid, a valve housing provided with an inner rotatable hollow valve mounted on the side of said tank above the liquid level, a tubular connection between the tank and valve exposing a portion of said hollow valve to the tank interior, a pipe projecting from said hollow valve through said tubular connection to the tank and directed downwardly into the liquid, said tubular connection being relatively large to permit oscillation of said pipe upon rotary movement of said valve, and a float on said liquid connected for operating said valve upon change in liquid level.
